(57) **CLAIM**

The ornamental design for a headset, as shown and described.

DESCRIPTION

FIG. 1 is an isometric view of a top, front, and right side of an ornamental design for a headset;

FIG. 2 is a front elevational view of the headset of FIG. 1; FIG. 3 is a rear elevational view of the headset of FIG. 1; FIG. 4 is a right side elevational view of the headset of FIG. 1;

FIG. 5 is a left side elevational view of the headset of FIG. 1;

FIG. 6 is a top plan view of the headset of FIG. 1; and, FIG. 7 is a bottom plan view of the headset of FIG. 1.

The dash-dash-dash lines illustrate portions of the headset that form no part of the claimed design.

1 Claim, 7 Drawing Sheets
